ORNAMENT FOR A VEHICLE BODY

Richard A. Teague, Rochester, Mich., assignor to Studebaker-Packard Corporation, a corporation of Michigan

Application August 4, 1954, Serial No. 31,735

Term of patent 14 years

(Cl. D14—6)

FIG. 1

FIG. 2

FIG. 3

FIG. 4

Figure 1 is a perspective view of an ornament for a vehicle body shown in reduced scale embodying my new design;

Figure 2 is a face view thereof; and

Figures 3 and 4 are sectional views taken along the lines 3—3 and 4—4 of Figure 2.

The broken line disclosure of an automobile in Figure 1 is shown only for purposes of illustration. The dominant features of my design reside in the full line portions of the drawing.

What is claimed is:

The ornamental design for an ornament for a vehicle body, as shown and described.
